(57) **CLAIM**

The design for a disposable vial, as shown and described.

DESCRIPTION

FIG. 1 is a perspective view of a disposable vial showing my new design;

FIG. 2 is a top plan view thereof;

FIG. 3 is a side elevational view thereof;

FIG. 4 is a side elevational view thereof; and,

FIG. 5 is a side elevational view thereof.

The bottom plan views of all embodiments are essentially identical to the top plan views.
